UNITED STATES PATENT OFFICE.

JOHN D. RUSS, OF SPENCER, WEST VIRGINIA.

PISTON FOR INTERNAL-COMBUSTION ENGINES.

1,063,602.

Specification of Letters Patent.

Patented June 3, 1913.

Application filed August 3, 1912. Serial No. 713,100.

To all whom it may concern:

Be it known that I, JOHN D. RUSS, a citizen of the United States, residing at Spencer, in the county of Roane and State 5 of West Virginia, have invented new and useful Improvements in Pistons for Internal-Combustion Engines, of which the following is a specification.

The object of this invention is to provide 10 a novel form of piston for internal-combustion engines, provided with means whereby perfect lubrication thereof is insured at all times.

With this object in view, the invention 15 resides in the novel construction, combination, and arrangement of parts, as will be hereinafter fully described in the specification, summed up in the claims, and illustrated in the drawing.

20 In the accompanying drawing, forming part of my specification, and in which like letters of reference indicate corresponding parts throughout the several views, I have illustrated a form of embodiment capable 25 of carrying out the underlying principles of the invention.

In this drawing: Figure I is a fragmentary, vertical, transverse section of a piston equipped with my improvements; 30 and Fig. II is a horizontal section on the line 2—2, Fig. 1. Fig. III is a fragmentary sectional view of the piston and its crank-shaft.

Referring, now, in detail to the drawing: 35 1 designates the piston, and 2 the piston rod, which is provided with a longitudinally-extending, internal channel or port 3, for the passage of lubricant therethrough.

40 4 is a transverse partition carried interiorly of the piston 1, toward the head 1^a thereof, and detachably secured to said piston in any suitable manner, as by screws 5. There is thus formed, between said partition and head, a chamber 6^a. Projecting 45 through the partition 4 is a lubricant-distributing member, comprising a tube 7 extending through said partition and having, at its end, radial extensions, or hollow, open-ended arms, 8. At the bottom, the tube 7 50 communicates with the end of a flexible tube 9, the other end of which is arranged in communication with the upper end of the port 3. The provision of a tube 9 which is flexible is important, as the flexibility permits 55 continuous communication and passage of lubricant between the tube 7 and the

port 3. The circumferential side wall of said chamber 6^a is provided with a plurality of apertures 10, extending therethrough.

In the chamber 6^a is an inverted cup 11 (that is to say, a cup having a circumferential side wall bearing against the circumferential side wall of the piston 1, and a bottom wall arranged near to and parallel with the head 1^a of the piston 1). The cup 11 60 is, as shown, constructed of foraminous, or screen, material. Inside the cup is disposed a body of absorbent material 6 (preferably heat-resisting), adapted to draw lubricant through the channel 3, and tubes 9 and 7, 65 by capillary attraction. The cup 11 is provided for particular purposes: First, its function is to constitute a receptacle, readily removable from the piston 1, for the absorbent material 6. As shown, the cup is 70 formed of reticulated, wire-mesh material, which, while preventing the exit of the coarse absorbent material 6 therethrough, permits the oil to escape through the interstices of the wire-mesh cup. The absorbent 75 material 6 is thus prevented from penetrating into the channels 10 in the piston 1, thus choking the same. Secondly, by reason of the provision of this cup, when it is desired to clean or repair the interior of the 80 piston 1, all that has to be done is to remove the partition 4, when the cup 11 may be removed, with the absorbent material therein 85 in a body.

The operation is apparent: The lubricant 90 passes through the channel or port 3, through the communicating tubes 9 and 7, into the absorbent material 6, thence out through the openings 10, thus thoroughly lubricating the piston 1, as it reciprocated in its cylinder 95 (not shown).

From the above description, taken in connection with the drawing, the many advantages of my invention will be apparent, especially to those skilled in the art to which the 100 invention appertains.

I am aware that various modifications in detail may be resorted to; but all such as come within the terms of the appended claims constitute no departure from the 105 spirit of the invention, and fall within the scope and purview thereof.

The piston 2 is operatively associated, at its lower end, as usual, with its crank-shaft 13. Extending longitudinally and internally 110 of the crank-shaft is a canal 20, having branches 19 and 18, tapped, at appropriate

points, by screw-plugs 21, 21, 21, by removing which access may be had to the canal for cleaning, or the like.

14 designates a bearing, through which 5 the crank-shaft 13 extends and in which it is rotatably supported. Said bearing carries a lubricant-cup 15 communicating with a passage 16 extending vertically from the periphery of said bearing to the longitudinal 10 bore thereof. The portion of the crank-shaft 13 which is within the bearing 14 is provided with a circumferential groove 17^a, communicating with a plurality of ports 17, extending transversely through said crank- 15 shaft and intersecting said port 18. The lower portion of the port 3 is provided with an annular extension 2^a surrounding the crank shaft 13, and communicating with such extension is a plurality of passages 22 20 extending through the crank-shaft and intersecting the passage 20. In the operation of the engine, the lubricant passes from the cup 15 through the ports 16, 17, 18, 19, 20, and 22 into the extension 2^a, and thence into 25 the port 3.

Having thus fully described my invention, what I claim as new, and desire to secure by Letters-Patent of the United States is:

1. In a piston, a partition carried trans- 30 versely therewithin, near one end thereof, forming a chamber therebetween and the head of the piston, said chamber having apertures through the circumferential side wall thereof, a cup-shaped member disposed 35 within said chamber and formed of reticulated, wire-mesh material, and a body of absorbent material contained within said cup-shaped member.
2. In a piston, a partition carried trans- 40 versely therewithin, near one end thereof, forming a chamber therebetween and the head of the piston, said chamber having apertures through the circumferential side wall thereof, a cup-shaped member disposed

within said chamber and formed of reticulated, wire-mesh material, a body of absorbent material contained within said cup-shaped member, and means projecting through said partition for supplying lubricant to said absorbent material. 45

3. In a piston, a partition carried transversely therewithin, near one end thereof, forming a chamber therebetween and the head of the piston, said chamber having apertures through the circumferential side 50 wall thereof, a cup-shaped member disposed within said chamber and formed of reticulated, wire-mesh material, a body of absorbent material contained within said cup-shaped member, a piston-rod having an internal, longitudinally-extending lubricant- 55 passage, and means for supplying lubricant from said lubricant-passage to said absorbent material, comprehending a flexible tube projecting through said partition and communicating with said lubricant-passage. 60

4. In a piston, a partition carried transversely therewithin, near one end thereof, forming a chamber therebetween and the head of the piston, said chamber having 70 apertures through the circumferential wall thereof, a cup-shaped member disposed within said chamber and formed of reticulated, wire-mesh material, a body of absorbent material contained within said cup-shaped member, and a lubricant-distributing member also disposed within said cup-shaped 75 member, and comprising a tube projecting through said partition and having, at its end, radial, hollow, open-ended arms. 80

In testimony whereof I have hereunto set my hand in presence of two subscribing witnesses.

JOHN D. RUSS.
